F. A. HART.
TYPEWRITING MACHINE.
APPLICATION FILED JAN. 3, 1919.

1,355,395.

Patented Oct. 12, 1920.

UNITED STATES PATENT OFFICE.

FREDERICK A. HART, OF NEW BRITAIN, CONNECTICUT, ASSIGNOR TO UNDERWOOD COMPUTING MACHINE COMPANY, OF NEW YORK, N. Y., A CORPORATION OF NEW YORK

TYPEWRITING-MACHINE.

1,355,395.

Specification of Letters Patent.

Patented Oct. 12, 1920.

Original application filed July 14, 1915, Serial No. 39,751. Divided and this application filed January 3, 1919. Serial No. 269,472.

To all whom it may concern:

Be it known that I, FREDERICK A. HART, a citizen of the United States, residing in New Britain, in the county of Hartford and State of Conn., have invented certain new and useful Improvements in Typewriting-Machines, of which the following is a specification.

One object of the present invention is to provide improved column-selecting means suitable for use in writing machines, especially machines of the type known as combined typewriting and computing machines. In such machines it is frequently desirable to select columns for different purposes, as, for instance, in a combined typewriting and computing machine, certain columns may be automatically selected to serve for adding purposes, and others may be automatically selected to serve for subtracting purposes, while others may be used for neither adding nor subtracting. It is found that in machines hitherto in use, the operatives, who are ordinarily far from being expert mechanics, are extremely likely to make errors resulting from the wrong selection of columns, or the selection of a column which may be in the right place, but of which the selecting mechanism is automatically connected to perform the wrong function.

In typewriting machines, tabulating stops are well known, and such stops are frequently used in combined typewriting and computing machines. In one advantageous form of the present invention, the tabulating stops are utilized both as denomination-selecting means, and for the purpose of determining whether the machine shall be automatically set to add or subtract in the columns in which they are effective. Each stop thus constitutes a composite tappet. Where it is not desired to use the column-stops for denomination selectors, said column-stops may, nevertheless, be provided with devices which determine whether said stops shall selectively cause addition or subtraction. In order to provide either the simple tabulating or the denomination-selecting type of stops with as many mnemonic safety reminders as possible, it has been found convenient in the present invention to color the stops, so that they will be distinguishable at a glance, even by those who do not understand the mechanics of the stops. For this

purpose, it is found convenient in the present invention to have the stops which serve for addition white or nickel-plated, whereas those which serve for subtraction may be black, and those which serve for tabulating purposes only, may be red or copper-plated. In order to further safeguard the operative from making mistakes, it is found convenient to form the stops or denomination-selecting blocks in such a way that they cannot be incorrectly placed on the rack-bar on which they are adjustably mounted.

This application is a division of my application No. 39,751, filed July 14, 1915 (now Patent No. 1,296,953, dated March 11, 1919).

Other features and advantages will hereinafter appear.

In the accompanying drawings,

Figure 1 is a sectional side view of an Underwood-Hanson combined typewriting and computing machine, showing my invention as applied thereto, the showing being principally in section and largely diagrammatic.

Fig. 2 is a side view of a subtraction stop.

Fig. 3 is a rear view of the same.

Fig. 4 is a side view of an adding stop.

Fig. 5 is a rear sectional view on line 5—5 of Fig. 4.

Fig. 6 is a side view of a neutral stop.

Fig. 7 is a front view of the same.

Fig. 8 is a fragmentary rear view of the parts seen in Fig. 1, when the carriage is entering an adding zone.

Fig. 9 is a skeleton perspective view, showing a decimal-tabulating stop just beginning to set the machine to subtraction.

In the usual Underwood typewriting machine, numeral keys 1 and alphabet keys 2 depress key-levers 3 to swing type-bars 4 upwardly and rearwardly, so that types 5 thereon print against the front side of a revoluble platen 6, in the usual traveling carriage 7. The type-bars 4 for this purpose are journaled on the usual segment ring 8, and as they approach the platen, each type-bar 4 actuates a universal bar 9 by means of a heel 10, for the purpose of causing the typewriter carriage to be drawn along one step by means of its usual spring-barrel 11. To cause this step-by-step feeding, the universal bar 9 actuates the usual dogs 12 and 13, which alternately engage the usual escapement wheel 14, said escapement wheel

connected to the usual pinion 15, meshing with the usual rack 16, pivotally connected to the typewriter carriage. As the typewriter carriage moves along in the adding zone, the numeral keys set up numbers, as in the Underwood-Hanson machine, in a temporary register in one denomination after another as said numbers are printed, and said registered numbers are later carried 10 into the usual computing wheels, not shown.

The computing mechanism may comprise denomination-selecting devices or tappets 26, which include the usual cam face 27, said face, as the carriage travels along, being 15 adapted to engage the upper ends of denominational rods 28 and slightly move said rods downwardly so that a combination of elements may be set up corresponding to the number printed by the numeral keys, so that 20 said number may be transferred to the dial wheels by means of a general operator; the denominational bars being depressed one after another in the adding zone by the tappet 26.

25 In order to rapidly position the typewriter carriage in and at the computing zone, the machine may be provided with the usual Underwood decimal tabulating mechanism, which includes a plunger or counter-stop 40 which may be moved into the path 30 of the column stops 41 mounted on the rack-bar 42, said rack-bar forming part of the usual Underwood typewriter carriage 7. To position the carriage, a stop and counter-stop arrest the carriage after being released 35 by the usual carriage-release devices, not shown herein.

In the present invention, as herein illustrated, the rack-bar 42 is shown as having 40 only a single set of teeth 44 thereon, said teeth being on the under side, and each column stop is herein shown as provided with two spaced side walls 45 and 46, which are adapted to engage said teeth and comprise openings by which they engage the rack-bar so as to overlie the stop bar 42. These side walls are spaced so as to embrace two or more consecutive teeth 44, so 45 as to give a solid wide base for the stop, while the teeth 44 with which they coöperate are set at letter-space intervals. The side walls 45 and 46 are kept spaced apart from each other by spacing sleeves 47, said sleeves surrounding rivets 48 by which the 50 side walls are joined. In the construction herein shown, two of the rivets 48 are placed in the portions of the walls which overlie the rack-bar 42, and these rivets and their spacing members 47 are located sufficiently 55 near the inside edge of said walls to prevent said stop from being inserted upside down on the rack-bar, this prevention resulting from the fact that if it is attempted to insert a stop upside down, one of its spacing members 47 will strike the ends of the rack

teeth 44, and thus prevent the stop from being inserted. Two of the rivets and spacing members 48 and 47 are placed at the opposite outer end of the stop, thus giving firmness to the structure. Said outer end 70 is formed as a relatively long continuation 49 of the remainder of the stop, said continuation being slotted at 50, so that said slot is a continuation of the opening by which the stop embraces the rack-bar 42, 75 this slot giving the parts a slight springiness to enable the stop to accommodate itself to slight variations in the size of the rack-bar 42, even though it fits all bars 42 tightly enough not to jar off in operation. 80

The parts of the walls 45 and 46 which embrace the rack-bar 42 are largely identical in form, but the right-hand wall 45 of the stop (as viewed by the operative when sitting at the machine) is extended downward to coöperate with the counter-stop 40 described above, whereas the wall 46 is too shallow to reach the counter-stop even when the said counter-stop is elevated. The stop is cut away at the corners 52 and 53 which would ordinarily strike the rack-bar as the stop is inserted, and the lower corner 53 of each side is beveled on the slope of the cut-away portion in order to enable it to enter the rack-bar 42 easily, even if not quite accurately positioned. When one of these stops, therefore, is inserted on the rack-bar 42, and is used to arrest the typewriter carriage, it will be observed that the side 46 which does not arrest the carriage passes 90 over the counter-stop 40 idly, and the carriage is arrested by the other side 45 of the stop when that one reaches the counter-stop. Both the counter-stop and the arresting side 45 of the column stop are beveled in the 95 manner customary in Underwood typewriting machines, and for the same purpose. 100

The stop thus described is shown in Figs. 6 and 7. This column stop is particularly well adapted to be used for operating the ordinary automatic devices for driving the general operator of the Underwood-Hanson machine. One form of said devices is shown in the patent to John L. Thornton, No. 1,283,360, dated October 29, 1918, wherein 110 the general operator is adapted to be driven by a motor.

The stop shown in Fig. 4 is enabled to start the motor, and for this purpose said stop is provided with a projection 63 extending 120 downwardly from its wall 45, which projection may form an extension of the part of the stop which coöperates with the counter-stop 40, if the stop is also used as a column stop. This projection, when the carriage 125 moves out of the adding zone, rides over and cams downward a starting dog 64 on a lever pivoted at 65 and connected by a downwardly extending draw link 66 to the bottom of the machine, where it is connected 130

to parts which control the motor, substantially in the manner shown in said Patent No. 1,283,360.

Whenever the typewriter carriage moves 5 out of the adding zone, the extension 63 of the stop 41 draws the draw-link 66 upward, thereby starting the motor to drive the general operator. The motor then reciprocates 10 the general operator through a forward and return movement to carry the number into the dial wheels.

In addition to adding, the present machine is adapted to subtract, which may be brought about by a cam bar extension 78 of 15 the starting stop 41, such an extension being shown in Fig. 3. This extension is formed as a bar extending up between the plates 45 and 46. The rear rivets pass through the bar 78 and the spacing members 48 and 47 20 engage it, so that it forms a part of the body of the stop, the lower end of said bar being bent out horizontally and beveled at the ends so as to extend over just the width of an adding column. This cam bar extension 78, 25 as the carriage rides along, strikes a subtraction dog 79 on a lever 80, which lever is pivoted at 65, so that when said lever is cammed down by the cam bar extension 78, it draws upwardly a draw link 81 to cause 30 the computing mechanism to be set to subtract. This subtraction mechanism may be substantially identical with that shown in said Patent No. 1,283,360.

The subtraction dog and the computation-starting dog are both of them so constructed 35 that the carriage will be effective on them only during its forward feeding movement, and for this purpose are formed as pivoted bodies 117 journaled on their levers 80, 119, 40 said levers being each provided with set screws 120 against which said dogs abut when the carriage is fed forwardly, but allowing said dogs to swing idly in the opposite direction, and being also provided 45 each with a wire spring, not shown, which holds its dog in effective position, but is weak enough to yield on the return stroke of the carriage.

If it be desired to utilize the stops as 50 nomination-selecting devices, the adding and subtracting dogs may be provided with the tappets 26, above referred to, said tappets being pivoted on blocks 122 lying within one arm of the dog and riveted thereto, said 55 tappets being of the usual form, having cam faces 27 which are adapted to cam downwardly the denominational bars 28, which for this purpose have correspondingly cammed faces. The blocks 122 are advantageously fast to only one wall of the 60 stop. During the forward feed of the carriage, any dog 27 lies with its flat face against the right-hand wall of its stop so that its cam face is held in effective position;

but on the return stroke of the carriage, said 65 tappet is able to swing on its pivot to an ineffective position, its left-hand side (as viewed by the operative when sitting before the machine) being for this purpose rounded off sufficiently to allow for this action. The 70 tappet is held to its block 122 by a screw 123 forming the pivot on which it swings, and a spring 124 constantly urges the tappet to the position in which it will be effective on the forward stroke of the carriage, said 75 spring coiled about a couple of rivets 125 within the body of the slot.

The machine is provided with a scale plate 132, suitably mounted on the carriage adjacent the column-stop rack-bar 42, for the 80 purpose of enabling the operative to insert the stops 41 at any required denomination without going to the trouble of counting up letter-spaces, the notations on said scale corresponding to the notations on the ordinary scale 133 at the front of the typewriter carriage.

This scale plate, as seen in Fig. 1, is just about on a level with the upper shoulders 134 of the various stops. The scale is advantageously so mounted that said shoulders just catch in front of the scale when a stop is pushed all the way home, and thus the stops may be said to be semi-locked in place. The scale 132 and its mountings are 95 limber enough so that the mere act of putting the finger under the scale to remove a stop will release said scale from the shoulders 134.

In order to visibly indicate to the operative which side of the stop is to be read in connection with the scale 132, the wall 45 of the stop, by which the stop is arrested in tabulating, is prolonged at 135 beyond the rearmost rivet 48, thus forming sort of 105 an indicator, while the other side 46 is rounded off nearly to the shape of the spacing member 47.

It will be noted from the subtraction stop shown in Fig. 12 that the bar 78 thereof is 110 effective over nine letter-spaces; this being the number of letter-spaces covered by the register in the ordinary Hanson machine. With registers having a different capacity, correspondingly different subtraction bars 115 78 should be used.

The relationship of the starting and subtraction dogs 64 and 79 to the rest of the mechanism is such that the starting dog is effective in the letter-feed of the carriage, 120 which takes place as a numeral key rises after writing a digit in the units column. The subtraction dog is so set with reference to the subtraction bar 78, that the machine goes to subtraction immediately the denomination-selector 27 enters the adding zone 125 and becomes ineffective in the same space that the starting dog becomes effective.

Variations may be resorted to within the scope of the invention, and portions of the improvements may be used without others.

Having thus described my invention, I

5 claim:

1. A stop comprising, in combination, a frame, including side walls and spacing members for maintaining the ends of said side walls fixed relatively to each other, an 10 extension of each side wall constituting a tooth adapted to enter notches between teeth on one side of a rack bar, and a second extension of each of said side walls to engage the opposite side of said rack bar.

15 2. A stop comprising, in combination, a frame, including side walls and spacing members for maintaining the ends of said side walls fixed relatively to each other, an extension of each side wall constituting a 20 tooth adapted to enter notches between teeth on one side of a rack bar, a second extension of each of said side walls to engage the opposite side of said rack bar, a selector-dog pivoted on said frame to swing about an 25 axis parallel to said side walls, a stop limiting the movement of said dog in one direction, and yielding means normally holding said dog against said stop.

3. A stop comprising, in combination, a 30 frame, including side walls and spacing members for maintaining the ends of said side walls fixed relatively to each other, an extension of each side wall constituting a tooth adapted to enter notches between teeth 35 on one side of a rack bar, a portion of one of said teeth being adapted to coöperate with a counter-stop, and a second extension of each of said side walls to engage the opposite side of said rack bar.

40 4. A stop comprising, in combination, a frame, including side walls and spacing members for maintaining said walls substantially fixed relatively to each other, an extension of each side wall constituting a 45 tooth adapted to enter notches between teeth on one side of a rack bar, a second extension of each of said side walls to engage the opposite side of said rack bar, and means on 50 one of said walls adapted to operate a tripping device.

5. The combination with two side walls, of spacing members holding said walls apart, devices for holding said walls to form a unitary structure, an opening in said walls 55 adapted to embrace a rack bar, an extension of one of said walls forming an arresting member to constitute the structure of a column stop, and an extension of said extended wall adapted to operate a tripping 60 mechanism.

6. The combination with two side walls, of spacing members holding said walls apart, devices for holding said walls to form a unitary structure, an opening in said walls 65 adapted to embrace a rack bar, an extension

of one of said walls forming an arresting member to constitute the structure of a column stop, and a bar projecting from said structure, secured by said spacing members and rivets between said walls and against 70 one of them and bent at right angles to the outside of said walls to form a camming member having rounded ends.

7. An assortment or set of stops for use 75 adjustably upon a rack bar having teeth on one side only, each of said stops comprising side walls, spacing means for maintaining said side walls fixed relatively to each other, an extension of each of said walls constituting a tooth to engage between the teeth on 80 the rack bar, and a second extension of each of said side walls to engage the opposite side of the rack bar, one of said stops having a column-stop portion on the tooth of one of said side walls, a second stop provided in 85 addition to a column-stop portion on one of its teeth, with a column-selector-dog and means to operate a tripping mechanism, and a third stop constructed to perform the same 90 functions as the second stop, and, in addition, having means to trip subtraction-setting mechanism, each of said stops having a distinctive appearance.

8. An assortment or set of stops for use 95 adjustably upon a rack bar having teeth on one side only, each of said stops comprising side walls, spacing means for maintaining said side walls fixed relatively to each other, an extension of each of said walls constituting a tooth to engage between the teeth on 100 the rack bar, and a second extension of each of said walls serving to engage the opposite side of the rack bar, one of said stops having a column-selector-dog and means to operate 105 a tripping mechanism, and a second stop constructed to perform the same functions as the first stop, and, in addition, having means to trip subtraction-setting mechanism, each of said stops having a distinctive appearance.

9. The combination with a rack bar, of a 110 column stop adapted to be inserted on said rack bar, teeth on said rack bar, spaced walls forming a part of said stop, engaging teeth on said rack bar separated by an interval of 115 more than one tooth, holding members holding said walls together to make said stop an integral member, an opening in said walls adapted to embrace said rack bar, and a long extension of said opening adapted to permit 120 said walls to yield slightly to accommodate the stop to slightly varying sized rack bars and adapted to grasp all such rack bars firmly.

10. The combination with a rack bar, of a 125 stop settable thereon comprising an elongated frame having side walls and means for holding the same in spaced relation, a tooth adapted to enter between teeth on one side of said rack bar extending from each of 130

said walls, and an extension of each side wall spaced from the tooth on the same wall, so that the extension and the tooth may embrace said rack bar.

5 11. The combination with a rack bar having teeth on one side only, of a stop settable thereon comprising two parallel plates, each of said plates having a slot with an open end, the portions of said plates on one side 10 of the slots forming teeth to enter notches between the teeth on the bar, the slots being of sufficient width so as to receive said rack bar, and a spacer between portions of the plates on the sides of the slots opposite the 15 teeth, said spacer being positioned so closely to said slots as to engage the sides of the teeth of the rack bar when an attempt is made to insert the stop in inverted position.

12. The combination with a stop bar 20 having teeth on one side only, of a stop settable thereon comprising two parallel plates, each of said plates having an open-ended slot of such width that, when a portion of each plate on one side of the slot is inserted 25 between the teeth of the stop bar, the opposite portion may be passed over the opposite side of the bar, and means to prevent the setting of said stop in inverted position on said bar.

30 13. The combination with a rack bar having teeth on one side and having no teeth on the opposite side, of a column stop adapted to engage said rack bar, said stop having an elongated open-end slotted portion adapted 35 to yield slightly to enable the stop to grasp the rack bar firmly, and said slotted portion comprising teeth and an opposite portion to engage said rack bar over a considerable space on the smooth side of said 40 rack bar, so as to insure steadiness of said stop when placed on said rack bar.

14. The combination with a stop bar having teeth on one side only, of a stop settable thereon comprising two parallel plates, each 45 of which has an open-ended slot of sufficient width near its open end to receive the stop bar, and being narrower for the rest of its length, thereby preventing the stop from being placed too far on said stop bar, the 50 lengths of the slots rendering the stop more flexible to enable the slotted plates to be spread in placing the same on the stop bar, so that the stop will be more firmly set thereon.

55 15. The combination with a rack bar, of a box-like stop adapted to embrace said rack bar, walls forming the sides of said box-like stop adapted to engage with teeth on said rack bar, a scale associated with said rack 60 bar, and an extension of one of said sides adapted to indicate on said scale the letter-space at which said stop is effective; said scale adapted to lock said stop to said rack bar, said stop having a shoulder to engage 65 said scale to be locked thereby, and said

scale and its mountings being sufficiently resilient to permit finger pressure to lift said scale clear of the stop which it locks.

16. The combination with a rack bar, of a box-like stop adapted to embrace said rack 70 bar, walls forming the sides of said box-like stop adapted to engage with teeth on said rack bar, a scale associated with said rack bar, an extension of one of said sides adapted to indicate on said scale the letter-space 75 at which said stop is effective, and devices associated with said stop, to prevent placing of said stop in inverted position on said rack bar, so that its extended side will indicate the true denomination on said scale. 80

17. In a stop, two side walls separated from each other and adapted to engage separate teeth, an extension of one of said walls adapted to coöperate with a scale, and holding means for holding said sides together 85 adapted to selectively indicate the proper setting of said stop.

18. The combination with a rack bar, of a box-like stop adapted to embrace said rack bar, walls forming the sides of said box-like 90 stop adapted to engage with teeth on said rack bar, a scale associated with said rack bar, an extension of one of said sides adapted to indicate on said scale the letter-space 95 at which said stop is effective, and a denomination-selecting device located between the walls of said stop.

19. The combination with a stop bar having teeth on one side only, of a stop settable thereon and adapted to engage the bar along 100 a portion of its length corresponding to a plurality of tooth spaces, and comprising a plate having an open-ended slot of sufficient width at its open end to receive the stop bar therein, and being narrower for 105 the rest of its length to prevent the stop from being placed too far on said bar, the additional length of said slot rendering the plate more flexible to permit spreading of the slotted end of the plate in placing the 110 same on the bar to insure a firmer setting for the stop.

20. The combination with a stop bar having teeth on one side only, of a stop settable thereon and adapted to engage the bar along 115 a portion of its length corresponding to a plurality of tooth spaces, and comprising a plate having an open-ended slot to receive the stop bar, and a shoulder at the side of the slot to limit the insertion of the stop bar, 120 said slot being extended beyond said shoulder to render the plate more flexible to permit spreading of the slotted end thereof in placing the stop on the bar, thereby insuring a firmer setting of the stop on the 125 bar.
